Patented Apr. 2, 1918.

WILLIAM MCKENZIE STEWART

UNITED STATES PATENT OFFICE.

WILLIAM MCKENZIE STEWART, OF TORONTO, ONTARIO, CANADA.

OIL-HEATER.

1,261,176.

Specification of Letters Patent.

Patented Apr. 2, 1918.

Application filed December 30, 1916. Serial No. 139,830.

To all whom it may concern:

Be it known that I, WILLIAM MCKENZIE STEWART, of the city of Toronto, in the county of York, in the Province of Ontario, 5 Canada, have invented certain new and useful Improvements in Oil-Heaters, of which the following is the specification.

My invention relates to improvements in oil heaters and the object of the invention is 10 to devise a heater of this class which will produce a complete vaporization of the oil and prevent the depositing of carbon particles within the heater and thereby provide a heater having a maximum heating efficiency 15 which will be cleanly and odorless and it consists essentially of the following arrangement and construction of parts as hereinafter more particularly explained by the following specification.

20 Figure 1, is a general perspective view of my apparatus.

Fig. 2, is a sectional view through one of the injectors employed in connection with my heater.

25 Figs. 3 and 4 are sectional views of the needle valves employed in my device.

In the drawings like letters of reference indicate corresponding parts in the various figures.

30 1 indicates a plurality of brackets or other supporting means designed to be secured within the fire pot of a furnace or stove. 2 indicates a rectangular open ended casing which rests in an up-ended position upon the brackets 1 preferably directly above the ordinary grate bars of a furnace when employed in a furnace. 3 indicates the main oil supply pipe provided with a controlling valve 4. 5 indicates the main water supply 40 pipe provided with a controlling valve 6. 7 indicates a pipe forming a vertical extension of the pipe 5, such extension leading vertically up into the casing 2 and provided at its upper end with a horizontally extending portion 8 leading into the center front of the casing, the extreme end being connected by suitable elbows to a further vertical extension 9, which is connected by an elbow 10 to an expansion tube 11 extending 45 rearwardly across the casing 2. The expansion tube 11 is substantially the same diameter as the pipe 7. 12 indicates an expansion tube of slightly greater diameter than the tube 11 and connected to the tube 11 by a 50 double elbow 13. 14 indicates an expansion tube of slightly greater diameter than the

expansion tube 12. 15 indicates a U-pipe connecting the expansion tubes 12 and 14 together.

16 indicates an expansion tube connected 60 to the expansion chamber 14 by a U-pipe 17 and of the same diameter as the expansion tube 14. 18 and 19 indicate expansion chambers of the same diameter but of slightly greater diameter than the tubes 16 65 and 14. 20 indicates a pipe connection between the expansion tube 16 and the expansion chamber 18. 21 indicates a U-pipe connecting the expansion chamber 18 to the expansion chamber 19. 22 indicates a vertical pipe connected at its upper end by an elbow 23 to the expansion chamber 19. 24 indicates an elbow connecting the lower end of the pipe 22 to a needle valve casing 25. 26 and 27 indicate the stem and controlling 70 handle respectively of the needle valve. 28 indicates an inverted T-joint, the upwardly extending arm of which is connected to the valve casing 25. 25* indicates the seat of the valve with which the needle end of the 80 stem 26 co-acts. 29 indicates a series of pipes arranged in circuitous formation forming a superheater.

30 indicates a vertical pipe, the lower end of which is provided with a horizontal forwardly extending portion 31 connected to the inner end of the horizontal arm of the T-joint 28. The upper end of the pipe 30 is provided with an extension 32 extending at right angles to the extension 31 and provided at its end with a further vertical extension 33 connected to one end of the superheater 29. The opposite end of the superheater is connected to a depending pipe 34, the lower end of which is provided with an 90 inward extension 35 terminating in an upturned portion 36 forming an open burner mouth. 37 indicates a cup surrounding such up-turned portion 36 designed to be filled with asbestos for a purpose which will hereinafter appear. 38 indicates a horizontal pipe connected by a T-joint 39 to the vertical pipe 30. 100

40 indicates a horizontal tube extending parallel with the expansion tubes 18 and 19. 105 The inner end of the tube 40 is provided with an elbow 41 to which is connected a vertical pipe 42, the lower end of which is connected by an elbow 43 to the pipe 38 hereinbefore described. The opposite end of the 110 tube 40 is provided with a T-joint 44. 45 indicates a vertical pipe connected at its

upper end to a nipple 46 (see Fig. 2). 47 indicates an injector nozzle extending into the T-joint 44 in central alinement with the tube 40. The opposite end of the nipple 46 is threaded into an internally threaded recess 48 formed in the outer end of the injector nozzle, the injector nozzle 47 being threaded at its outer end into a head 49 suitably secured within the T-joint 44. The 10 T-joint 39 is also provided with an injector similar to that above described and shown in Fig. 2 of the drawings, the nozzle thereof projecting into the pipe 30. At the lower end of the pipe 45 is provided a needle valve 50, 51 and 52 being the controlling handle and stem thereof respectively. 53 indicates a pipe forming a by-pass duct which is connected by a T-joint 54 to the pipe 22 intermediately of its height. The 20 opposite end of the pipe 53 is connected by a suitable joint 54^x to the valve casing 50. 55 indicates an elbow connected to the outwardly projecting arm of the T-44. 56 indicates a pipe depending from the elbow 55 and connected by an elbow 57 at its lower end to the pipe 3 hereinbefore described.

57^x and 58 indicate brackets secured to the front and back walls of the casing 2 and on which suitable portions of the pipe structure at the ends of the expansion tubes 18 and 19 rest whereby the whole structure is supported by the casing 2 on the brackets 1 in the interior of the furnace or stove.

Having described the principal parts involved in my invention I will briefly describe the operation of the same.

When starting my apparatus the valve 4 is opened allowing oil to flow through the pipe 3 upwardly through the pipe 56 into the pipe 40, then downward through the pipe 42, through the pipe 38, then upwardly through the pipes 30 and 32, through the superheating pipe 29 and from thence downward through the pipe 34 to the pipe 35 leading to the open mouth of the up-turned portion 36, which overflowing saturates the asbestos in the cup 37. This initial charge of oil is then lighted by the operator, the valve 4 being then closed. The flame thus 50 formed heats the pipe 40 causing the oil therein to expand and thus cause the oil to continue flowing out of the mouth of the burner 36 thus providing for the continuance of the flame. The valve 6 is then 55 opened allowing water to flow through the pipe 5, up the pipe 7 into the expansion tube 11, which expands such water into steam which then passes onwardly through the tubes 12, 14, 16, 18 and 19 gradually 60 expanding the steam into vapor, which passes down through the pipe 22. Part of this flow of steam passes through the pipe 53 to the valve 50, the other portion continuing on down the pipe 22 to the valve 65 25. The valve 50 is then opened allowing

a charge of steam to pass through the injector nozzle of the T-joint 44 and to be ejected into the charge of oil previously fed into the pipe 40. The valve 4 is then again opened to the required extent.

It may be stated that oil will not thoroughly mix with the large volume of steam forced thereinto and will, therefore, cause carbon deposits to form on the walls of the tubes. By injecting a small quantity of steam into the oil a thorough mixture is provided, which is fully vaporized and passes off without any carbon deposit. The mixture so formed passes down through the pipe 42, and through the pipe 38. The 80 valve 25 is then opened allowing the main body of the expanded water vapor passing down the pipe 22 to pass into the pipe 31 and into the pipe 30 mixing with the incoming vaporized oil passing from the pipe 38. The combined mixture then passes up the pipe 30, through the pipe 32, through the superheating pipes 29 and from thence down the pipe 34 to the burner 36, arriving at the burner in the form of a combustible 90 gas.

From this description it will be seen that I have devised a very simple form of oil burning apparatus in which all oil particles are thoroughly separated into vapor so that 95 when such vapor arrives in the form of gas at the burner nozzle a maximum efficiency is derived therefrom, also by the injection of a small quantity of steam into the oil as above described all liability for the oil to 100 carbonize on the interior walls of the tubes and pipes is avoided thereby providing a heater of maximum efficiency, which will be clean and obviate any danger of smell.

If desired the upper portion of the casing 105 above the brackets 57 and 58 and around the expansion tubes 18, 19, 16, 14, 11 and 12 and superheating pipes 29 may be filled with asbestos fuel, which thereby aids to retain the heat around such pipes and aids in producing 110 the necessary heat for vaporizing the oil.

What I claim as my invention is:

1. In an oil burning heater, an oil chamber, an oil supply pipe, a water supply pipe, a burner, a pipe connection between the oil 115 chamber and the burner, a pipe connection between the oil supply pipe and oil chamber, an expansion chamber element, a pipe connection between the water supply pipe and such element, a discharge pipe from the 120 expansion element having branches, one branch leading into the pipe extending from the oil chamber to the burner and the other branch extending directly to the oil chamber, and controlling valves for each branch. 125

2. In an oil burning heater, an oil chamber, an oil supply pipe, a water supply pipe and burner, a pipe connection between the oil chamber and the burner, a pipe connection between the oil supply pipe and oil chamber, 130

an expansion chamber element, a pipe connection between the water supply pipe and such element, a discharge pipe from the expansion element having branches, one branch leading into the pipe extending from the oil chamber to the burner and the other branch extending directly to the oil chamber, controlling valves for each branch, an injector nozzle located in the end of the oil chamber and to which the pipe leading thereto is connected, and an injector nozzle located in the end of the branch and extending into the pipe leading from the oil chamber to the burner.

15. 3. In an oil burning heater, the combination with an oil supply pipe and water supply pipe and burner, of a series of ducts for carrying the oil from the oil supply pipe to

the burner, means for vaporizing the water, means for injecting a portion of such vaporized charge of water into the oil fed to the burner, means for subsequently mixing the vaporized oil and water vapor with the main body of the vaporized water and finally conveying such mixture to the burner, a casing having open upper and lower ends surrounding the aforesaid apparatus, supporting brackets secured within the casing on which the aforesaid apparatus rests, and supporting means for the casing adapted to be secured to the fire pot of the furnace.

WILLIAM MCKENZIE STEWART.
